UNITED STATES PATENT OFFICE.

TROY P. BURTON AND SILAS W. FORD, OF DENVER, COLORADO.

DIRIGIBLE SPOTLIGHT.

Application filed February 16, 1926. Serial No. 88,669.

This invention relates to dirigible spotlights and has for an important object thereof the provision of a device of this character which may be very cheaply produced and which, at the same time, has a maximum flexibility or range of adjustment.

A further object of the invention is to produce a device of this character which may be very readily adjusted to vary the angle of the beam so that it will not annoy oncoming drivers and may, at the same time, be concentrated upon a desired portion of the roadway.

A further object of the invention is to provide a device of this character which may be completely reversed in its mounting so that it will direct its light rearwardly thereby permitting the device to be used as a trouble lamp when changing tires at the rear of the machine or performing some similar operation.

A still further object of the invention is to provide a device of this character which may be very readily assembled from its mounting so that it may be employed as a trouble light at any point.

These and other objects we attain by the construction shown in the accompanying drawings, wherein for the purpose of illustration is shown a preferred embodiment of our invention and wherein:

Figure 1 is a plan view of a spotlight mounting constructed in accordance with our invention;

Figure 2 is a rear elevation thereof;

Figure 3 is a section on the line 3—3 of Figure 1;

Figure 4 is an enlarged detail elevation of the inner end of the tube and the operating hand wheel;

Figure 5 is a section on the line 5—5 of Figure 4.

Referring now more particularly to the drawings, the numeral 10 indicates a suitable bracket which is adapted to be secured rigidly to the side member 11 of a windshield frame. This member includes spaced arms 13, the ends of which have mounted therein adjusting screws 14. The ends of the adjusting screws 14 are rounded and engage in similar rounded sockets 15 formed in the outer wall of a tube 16 intermediate the ends thereof and at a point arranged diametrically opposite to one another. The inner end of the tube 16 is provided with a serrated head 17 and in the bore of the tube is rotat-

ably mounted a shaft 18 upon the inner end of which is formed a head 19.

Between the head 19 and the adjacent head 17 of the tube a hand wheel 20 is splined upon the shaft 18 and has a serrated face 21 for coaction with the serrations of the head 17. A spring 22 surrounds the shaft between the head 19 and hand wheel and constantly urges the hand wheel into engagement with the head so that the shaft 18 is normally yieldably held against rotation. The outer end of the tube is engaged by a head 23 formed upon the shaft 18 and this head has parallel side faces 24 which are engaged by the ears 25 on a lamp casing 26. The head 24 and ears 25 are connected by a bolt 27 having a wing nut 28. This wing nut serves as a means for clamping the lamp casing 26 in angularly adjusted position with relation to the shaft and as a means for rendering the bolt 27 readily removable so that the lamp casing may be separated from its support and transported from place to place for use as a trouble light.

In the use of the device, the screws 14 will be adjusted to provide a sufficient friction against the tube to hold the same in angularly adjusted positions to which they may be moved. The horizontal angle of the beam of light projected from the lamp casing may be regulated by rotating the hand wheel 20 and the angular adjustment of the beam with relation to the line of movement of the car may be adjusted by swinging the tube upon its pivots. Operating means are thus provided for a substantially universal control of the lamp 26 from the interior of the car. It will, of course, be noted that by rotating the hand wheel, the position of the lamp casing may be completely reversed so that the beam is rearwardly directed instead of forwardly directed, as illustrated.

The construction hereinbefore set forth being obviously capable of a certain range of change and modification without materially departing from the spirit of the invention, we do not limit ourselves to such specific structure except as hereinafter claimed.

We claim:

1. In a spotlight mounting, a bracket adapted for attachment to a suitable support, a tube pivoted intermediate its ends to the bracket, a shaft rotatable in the tube, a lamp casing secured to the outer end of the shaft, the inner end of the shaft having a

- head, a hand wheel splined to the shaft and the adjacent end of the tube, means constantly urging the hand wheel against the inner end of the tube and coacting clutch faces upon the hand wheel and the tube.
2. In a spotlight mounting, a bracket adapted for attachment to a suitable support, a tube pivoted intermediate its ends to the bracket, a shaft rotatable in the tube, a lamp casing secured to the outer end of the shaft, the inner end of the shaft having a head, a hand wheel splined to the shaft and the adjacent end of the tube, means constantly urging the hand wheel against the inner end of the tube and coacting clutch faces upon the hand wheel and the tube, the lamp casing being angularly adjustable upon the outer end of the shaft.
3. In a spotlight mounting, a bracket adapted for attachment to a suitable support, a tube pivoted intermediate its ends to the bracket, a shaft rotatable in the tube, a lamp casing secured to the outer end of the shaft, the inner end of the shaft having a head, a hand wheel splined to the shaft and the adjacent end of the tube, means constantly urging the hand wheel against the inner end of the tube, coacting clutch faces upon the hand wheel and the tube and a connection between the lamp casing and the outer end of the shaft whereby the lamp casing may be readily removed therefrom.

4. In a spotlight mounting for vehicles, a bracket adapted to be secured to the windshield frame of a vehicle and having spaced arms, pivot elements adjustable through said arms, a tube having sockets intermediate its ends in which the pivot elements engage, a shaft rotatable in the tube and having a lamp casing secured to its outer end and means at the inner end of the shaft whereby the shaft may be rotated and held in adjusted positions with relation to the tube.
5. In a spotlight mounting for vehicles, a bracket adapted to be secured to the windshield frame of a vehicle and having spaced arms, pivot elements adjustable through said arms, a tube having sockets intermediate its ends in which the pivot elements engage, a shaft rotatable in the tube and having a lamp casing secured to its outer end, means at the inner end of the shaft whereby the shaft may be rotated and held in adjusted positions with relation to the tube including a hand wheel splined to the shaft, the inner end of the shaft having a head, a spring surrounding the shaft between the head and hand wheel and coacting clutch faces upon the hand wheel and the adjacent end of the tube.

In testimony whereof we hereunto affix our signatures.

TROY P. BURTON.
SILAS W. FORD.
